CLAIM

The ornamental design for a shoe upper, as shown and described.

DESCRIPTION

FIG. 1 is a right side elevational view of a shoe upper showing my new design which is the subject of this invention. The broken line showing a shoe sole is for environmental purposes only and forms no part of the claimed invention.

FIG. 2 is a top plan view thereof;

FIG. 3 is a bottom plan view thereof;

FIG. 4 is a left side elevational view thereof;

FIG. 5 is a front elevational view thereof; and FIG. 6 is a rear elevational view of the present invention.

FIG. 7 is a right side elevational view of an alternate embodiment of my invention; and

FIG. 8 is a top plan view of the alternate embodiment thereof;

FIG. 9 is a bottom plan view of the alternate embodiment thereof;

FIG. 10 is a left side elevational view of the alternate embodiment thereof;

FIG. 11 is a front elevational view of the alternate embodiment thereof; and

FIG. 12 is a rear elevational view of the alternate embodiment thereof;

Fig. 1.

Fig. 2.

Fig. 3.
